No. 727,755.

PATENTED MAY 12, 1903.

G. E. CUNNINGHAM.
FOLDING CAR STEP.
APPLICATION FILED NOV. 26, 1902.

NO MODEL.

UNITED STATES PATENT OFFICE.

GEORGE ERNEST CUNNINGHAM, OF MACON, GEORGIA.

FOLDING CAR-STEP.

SPECIFICATION forming part of Letters Patent No. 727,755, dated May 12, 1903.

Application filed November 26, 1902. Serial No. 132,923. (No model.)

To all whom it may concern:

Be it known that I, GEORGE ERNEST CUNNINGHAM, a citizen of the United States, residing at Macon, in the county of Bibb and State of Georgia, have invented a new and useful Folding Car-Step, of which the following is a specification.

The invention relates to improvements in folding car-steps.

10 The object of the present invention is to improve the construction of folding steps for railway-cars and to provide a simple, inexpensive, and efficient device designed to be applied to passenger-coaches and similar conveyances and adapted when extended to form a continuation of the stationary steps to obviate the necessity of using a box or similar device for the ingress or egress of persons.

20 A further object of the invention is to provide a folding car-step of this character which will be securely held in its folded position to prevent it from accidentally working outward and which may be quickly released and drawn outward from its folded position.

25 The invention also has for its object to provide a folding car-step which may be readily transferred from one side or end of a car to the other or from one car to another when desired.

30 The invention consists in the construction and novel combination and arrangement of parts hereinafter fully described, illustrated in the accompanying drawings, and pointed out in the claims hereto appended.

35 In the drawings, Figure 1 is a front elevation of a folding step constructed in accordance with this invention and shown folded. Fig. 2 is a side elevation of the same. Fig. 3 is a front elevation of the folding car-step, 40 the same being extended and arranged for use. Fig. 4 is a side view of the same. Fig. 5 is a sectional view, the step being folded and locked in such position. Fig. 6 is a detail sectional view illustrating the manner of 45 pivoting the hanger or riser bars. Fig. 7 is a detail view of one of the hanger or riser bars. Fig. 8 is a detail view of one of the supporting-bars.

Like numerals of reference designate corresponding parts in all the figures of the drawings.

11 designate side plates provided at their

upper edges with inwardly-extending horizontal flanges 2, secured by rivets 3 or other suitable fastening devices to the lower sides 55 of approximately U-shaped springs 4, which are arranged horizontally and which engage a stationary step 5 of a car. The U-shaped springs form resilient clamps for frictionally engaging the car-step to enable the folding 60 step to be readily applied to the same and to permit the folding step to be quickly transferred from one portion of a car to another or from one car to another, as desired; but the upper sides of the springs may be provided 65 with perforations 6^a for enabling them to be screwed or otherwise secured to a car. The lower sides of the springs are arranged at the lower faces of the flanges 2 of the side plates, and the friction is sufficient to hold the folding 70 step on a stationary car-step while the latter is being operated, as hereinafter explained. The side plates, which are provided with longitudinal slots 6, are connected by front and rear rods 7 and 8, having threaded ends extending through perforations of the plates and receiving nuts which are arranged on the outer faces of the plates. The slots 6, which have horizontal front portions, are provided with inclined inner portions, and they 75 receive slides 9, consisting of plates arranged on the outer faces of the sides or plates 1 and provided with lugs or enlargements 10, arranged in the slots. The slides are perforated for the reception of a rod 11, which pivotally and slidably connects a pair of hanger or riser bars 12 to the sides or plates 1, and the slides are adapted to move freely inward and outward in the slots. The hanger or 80 riser bars, which are provided at their upper 90 or inner ends with integral arms 13, are perforated for the reception of the transverse rod 11, and their lower or outer ends are perforated for the reception of a pivot 14 for connecting the supporting-bars 15 to the 95 riser-bars. The pivot preferably consists of a rod and the adjacent ends of the hanger or riser bars, and the supporting-bars are provided with curved edges 16 and 17 and with inwardly-extending lugs 18 and 19, which 100 limit the pivotal movement of the parts to permit the folding step to swing upward from the horizontal position (illustrated in Fig. 4 of the drawings) to a vertical position between

the hanger-bars and to swing downward therefrom. The supporting-bars are provided with inwardly-extending flanges 20, which are perforated for the reception of fastening devices for securing the step 21 to them. The step may consist of one or more pieces of wood or any other material, as will be readily understood. When the step 21 is swung upward between the hanger-bars from the position illustrated in Fig. 4 of the drawings, the hanger-bars are then adapted to be swung upward to a horizontal position and to be moved inward to arrange the parts, as illustrated in Figs. 1, 2, and 5 of the drawings. The front rod 7, which connects the sides or plates 1, is located slightly in rear of the front ends of the slots 6 and at a point below the same, and when the hanger-bars are drawn outward to arrange the step in the position shown in Fig. 4 they will engage the front rod, which will force them to the extreme front ends of the slots. It also forms a stop to prevent the step from moving inward accidentally from the position illustrated in Fig. 4. When the step is arranged as shown in Fig. 4, the arms 13 at the upper ends of the hanger or riser bars engage the lower sides of the springs 4 to form stops for preventing the lower portions of the hanger-bars from swinging rearward. The lugs 18 and 19 also limit the upper or inward movement of the step 21 and support the same in a substantially horizontal position when the parts are folded. The end of the upper side of each spring is beveled or cut away at 22 to enable the clamp to be readily engaged with the stationary step of a car and to permit the spring to be made of a strength to hold it in engagement with the stationary step when the folding step is pulled outward, as hereinafter explained, without requiring tools or other means for applying it to the step.

The step 21 is locked in its folded position by means of a pivoted catch 23, mounted between ears or flanges 24 of a plate 25 and having inner and outer arms arranged at an obtuse angle to each other. The outer arm is beveled to provide a pointed end or tooth 26 for engaging the lower face of the stationary step 5, and it is adapted to embed itself in the same, as clearly shown in Fig. 5. The inner arm of the catch is connected by a rod 27 with an operating-lever or trigger 28, pivoted between its ends at 29 to flanges or ears 30 of a plate 31, which is secured to the step 21 and which is provided with a lug or flange 32 for the purpose hereinafter described. The operating lever or trigger and the perforated ears or flanges are arranged in a slot or opening of the step 21, and one end of the trigger or lever is shaped into a grip or handle and is adapted to be engaged by the finger of the operator. The other end of the trigger or lever is arranged to engage the rod 27, which is provided with a head 33 and which passes through a guide 34. The guide 34 consists

of an L-shaped plate secured to the step and provided with a perforation to receive the rod 27, and a coiled spring 35 is interposed between the guide and the head 33 of the rod and is arranged on the latter. The spring is adapted to hold the catch in position for engaging the stationary car-step, and it maintains the catch in such engagement until the trigger or operating-lever is moved by the operator in the direction of the stop, lug, or flange 32. The operator grasps the handle portion of the trigger or lever and pulls the same outward when the parts are in the position shown in Fig. 5 until the handle portion reciprocates the rod 27 and throws the toothed or engaging portion of the catch out of engagement with the stationary step, and thereby releases the movable step. A continued outward pull on the trigger or operating-lever draws the movable step outward, and the parts are adapted to be readily arranged as shown in Fig. 4. In folding the parts the trigger is held by the operator to permit the catch to clear the stationary step, and as soon as the trigger is released the catch will be thrown into engagement by the spring. Any tendency of the step to move outward and upward along the inclined portion of the slot will operate to carry or force the catch more firmly in engagement with the stationary step, so that it will be impossible for the movable step to be accidentally thrown outward by the vibration of the car. The trigger and the lug 32 extend upward from the upper face of the movable step when the parts are arranged as shown in Fig. 4, and the said trigger is located at the hinged or rear edge between the hanger or riser bars, so that it will be out of the way. The catch and the adjacent parts of the locking mechanism are located at the lower face of the movable step when the latter is arranged as shown in Fig. 4.

It will be seen that the device is exceedingly simple and inexpensive in construction, that it possesses great strength and durability, and that it is adapted to be readily applied to and removed from the stationary step of a car. It will also be clear that the step is firmly held in its folded position and that it is securely supported in position for use and that it is adapted to readily slide inward and outward. The rod which connects the slides causes the same to move inward and outward simultaneously and prevents them from twisting or binding in the ways formed by the inclined slots. The rod is also adapted to receive and support the movable step when the latter is folded between the hanger or riser bars.

What is claimed is—

1. A folding car-step provided with a pair of horizontally-disposed approximately U-shaped springs forming clamps and arranged to frictionally engage a stationary car-step, whereby the folding car-step is detachably secured to the same, substantially as described.

2. The combination of a pair of horizontally-disposed approximately U-shaped clamps arranged to detachably engage a stationary car-step, sides depending from the clamps, a 5 movable step, and means for connecting the movable step with the said sides, substantially as described.

3. The combination of sides having slots forming ways, slides operating in the ways, 10 hanger-bars pivotally connected with the slides, a step connected with the hanger-bars, and a fixed device located below the ways and arranged to be engaged by the hanger-bars, whereby the slides will be forced to the 15 outer ends of the ways, substantially as described.

4. The combination of sides or plates provided with slots and having flanges at their tops, resilient clamps secured to the flanges 20 and arranged to engage a stationary step, slides operating in the slots, hanger-bars pivotally connected with the slides and provided at their upper or inner ends with arms to form stops, a movable step, and supporting-bars connected with the movable step and pivotally connected with the hanger-bars, 25 said bars being provided with means for limiting their pivotal movement, substantially as described.

30 5. A movable step, hanger-bars pivotally connected with the step, means for pivotally and slidably connecting the hanger-bars with the stationary step of a car, a locking device

mounted on the movable step and arranged to engage the stationary step, and operating 35 mechanism connected with the catch and located at the outer portion of the movable step when the parts are folded, substantially as described.

6. The combination of a support designed 40 to be secured to a stationary step and provided with inclined ways, a movable step operating in the ways and foldable within the support, and a locking device arranged upon the movable step when the latter is folded 45 and engaging the stationary step in position to be forced into the same by the outward movement of the movable step, substantially as described.

7. The combination of a foldable step arranged at an inclination when folded, a pivoted locking device located at the upper face of the foldable step in position for engaging the stationary step when the parts are folded, and an operating device arranged at the outer 55 edge of the foldable step when the parts are folded and at the inner edge of the same when the movable step is in position for use, substantially as described.

In testimony that I claim the foregoing as 60 my own I have hereto affixed my signature in the presence of two witnesses:

GEORGE ERNEST CUNNINGHAM.
